CLAIM

The ornamental design for a shirt as shown and described.

DESCRIPTION

FIG. 1 is a front view of a shirt showing our new design; FIG. 2 is a right side front perspective view thereof; and, FIG. 3 is a left side front perspective view thereof. The broken line immediately adjacent to and surrounding the photographic area defines the peripheral bounds of the claimed design and forms no part thereof. The broken lines depicting the remainder of the shirt form no part of the claimed design.
